DESIGN FOR A CURTAIN OR THE LIKE

Max Sadinoff, Brooklyn, N. Y.

Application April 28, 1934, Serial No. 51,565

Term of patent 3½ years

To all whom it may concern:

Be it known that I, MAX SADINOFF, a citizen of the United States, residing at 1766 Union Street, in the Borough of Brooklyn, city of New York, county of Kings, and State of New York, have invented a new, original, and ornamental Design for a Curtain or the like, of which the following is a specification, reference being had to the accompanying drawing, forming a part thereof.

The figure is a plan view of a curtain showing my new design.

The broken away portion indicated by the dotted lines contains two additional "chevron" sections identical with those illustrated in the other section shown in the drawing.

I claim:

The ornamental design for a curtain or the like as shown and described.

In testimony whereof I have signed this specification.

MAX SADINOFF.
